(57) **CLAIM**

The ornamental design for a support shelf, as shown and described.

DESCRIPTION

FIG. 1 is a front, perspective view of a support shelf showing our new design;

FIG. 2 is a front view thereof;

FIG. 3 is a rear view thereof;

FIG. 4 is a right side view thereof, the left side view being a mirror image of the right side view;

FIG. 5 is a top view thereof; and

FIG. 6 is a bottom view thereof.

FIG. 7 is a front, perspective view of the support shelf of FIG. 1 shown with additional environmental subject matter in the form of a partial support rod;

FIG. 8 is a front view thereof;

FIG. 9 is a rear view thereof;

FIG. 10 is a right side view thereof, the left side view being a mirror image of the right side view;

FIG. 11 is a top view thereof; and

FIG. 12 is a bottom view thereof; and,

FIG. 13 is a front, perspective view of the support shelf of FIG. 1 shown with additional environmental subject matter in the form of a partial support rod and a surrounding retail display system.

The features shown in broken lines are portions of the support shelf or environmental subject matter to the support shelf forming no part of the claimed design. The features shown in long dash-short dash bolded broken lines (see FIGS. 3, 6, 9, and 12) indicate the bounds of the claimed design and otherwise form no part of the claimed design.
